UNITED STATES PATENT OFFICE.

FRANK L. ORDWAY, OF SALEM, MASSACHUSETTS, ASSIGNOR TO PARKER BROS., INC.,
OF SALEM, MASSACHUSETTS, A CORPORATION OF MAINE.

CHINESE TILE GAME DEVICE.

Application filed February 5, 1924. Serial No. 690,733.

To all whom it may concern:

Be it known that I, FRANK L. ORDWAY, a citizen of the United States, and a resident of Salem, in the county of Essex and State of Massachusetts, have invented an Improvement in Chinese Tile Game Devices, of which the following description, in connection with the accompanying drawings, is a specification, like characters on the drawings representing like parts.

This invention aims to provide an improved device for use in playing Chinese tile games.

In the drawings, which show a preferred form of one embodiment of my invention:—

Figure 1 is a plan view of a device for holding tiles and counters, the tiles in place on the rack during the progress of the game;

Fig. 2 is a front elevation of the device and tile parts shown in Fig. 1;

Fig. 3 is a plan view of the device, with tiles, at the end of the game, the counter container uncovered and the rack tipped upwardly to show the faces of the tiles in the player's concealed hand;

Fig. 4 is an end elevation of the device and tiles in the position shown in Figs. 1 and 2;

Fig. 5 is an end elevation of the device and tiles in the relative positions shown in Fig. 3; and

Fig. 6 is a section on the line 6—6 of Fig. 3.

Referring to the drawings and to the preferred form of my invention selected for illustrative purposes, I have shown a counter container 1, preferably formed of wooden molding and presenting a longitudinally extending groove of substantial depth provided with transverse partitions which divide the groove into compartments 2, herein shown as of varying length, to hold counters 3 herein shown as sticks of varying length and/or color as ordinarily used in Chinese tile games. The ends of the container 1 are preferably of sheet form and of relatively strong and stiff material, providing at one side of the container and at each end thereof projecting portions which extend to one side of and above the level of the top of the container 1. Between these extensions, I have pivotally mounted a rack 5 which holds the tiles 6

ordinarily used in playing Chinese tile games.

When the rack is in its down position, as shown in Figs. 1, 2 and 4, the tiles thereon are concealed from the players other than the one behind the rack. The container 1 is provided with a cover 10, which during the progress of the game covers the counters and is in adjacency to the front of the rack, providing a shelf on which tiles to be exposed during the progress of the game may be laid. This cover is so mounted that at the end of the game it may be swung forwardly to permit access to the counters in the container, without disturbing the exposed tiles on the top of the cover. In the embodiment of my invention illustrated, the cover 10 remains in a generally horizontal plane during the entire movement thereof from the closed position shown in Fig. 4 to the open position shown in Fig. 6, being mounted at each end on pairs of parallel links 9, 9 of equal effective length between their respective pivots on the ends of the top 10 and on the ends of the container 1, thereby providing for parallel motion of the cover when manually opened and closed. The cover is preferably provided with two knobs 10' at each end thereof. Each of knobs may be mounted upon the same pivot with one of the links 9. Movement of the cover may be most easily effected by placing the thumbs in the rack adjacent the ends thereof and then placing the forefingers on the knobs 10' (or on the ends of the cover), when a slight forward movement of the forefingers will move the cover of the container to its opened position.

The rack 5, pivoted between the upstanding projections 4' of the ends of the container may conveniently be swung to the position shown in Fig. 5, after opening of the container, by grasping a suitable knob 11. The rack will remain in elevated position because held, preferably frictionally, between the more or less springlike projections 4' from the ends of the container. The weight and wide base presented by the container will prevent the device as a whole from being tipped over.

I will now describe the use of the device. At the start of the game, the player places his tiles upon the rack, where they are concealed from the other players, as best shown

in Figs. 1, 2 and 4. The cover of the counter container is closed until the game is finished. During the game the player may have occasion to transfer some of the tiles from the rack to the top of the cover so that such tiles will be exposed to the other players face upward. When the game has been completed and the player is to compute his score, showing the other players what he has in his concealed hand (on the rack), he first opens the counter container, preferably by moving forwardly the cover thereof with his forefingers, meanwhile holding the rack with his thumbs, and then tips up the rack 5 by a slight lifting on the knob 11, until his concealed hand is exposed as best shown in Figs. 3, 5 and 6.

After computation of the amount to be received or paid, as the case may be, appropriate additions to or removals from the counters in the container may be made. The opening of the container has not necessitated any movement of the tiles constituting the exposed portion of the hand, relative to the top of the container which serves as a shelf for their support.

While I have shown and described a preferred form of one embodiment of my invention, it will be understood that changes involving omission, substitution, alteration and reversal of parts, and even changes in the mode of operation, may be made without departing from the scope of my invention, which is best defined in the following claims.

Claims:

1. A device for use with Chinese tile games comprising, in combination, a container for counters, a removable top therefor presenting an upper surface for holding exposed tiles, connections between said top and said container providing for maintaining said top in generally horizontal position during movement of said top to open and close

said container, and a rack at that side of said container toward the player presenting a ledge for holding concealed tiles, said rack pivoted relative to said container and tiltable to permit exposure of the tiles normally concealed thereon.

2. A device for use with Chinese tile games comprising, in combination, a container for counters, a removable top therefor presenting an upper surface for holding exposed tiles, connections between said top and said container providing for maintaining said top in generally horizontal position during movement of said top to open and close said container, and a rack at that side of said container toward the player presenting a ledge for holding concealed tiles, said rack pivoted relative to said container and tilttable to permit exposure of the tiles normally concealed thereon, and said rack presenting an inclined tile-holding surface on which the thumbs of the player may rest during shifting of the top of said container by his forefingers.

3. A device for use with Chinese tile games comprising, in combination, a container for counters, a playing rack for holding tiles pivoted upon extended sides of said container, a cover for said container and connections providing for movement of said cover in a generally horizontal plane relative to said container.

4. A device for use with Chinese tile games comprising, in combination, a container for counters, a playing rack for holding tiles pivoted upon extended sides of said container, a cover for said container and a plurality of links pivoted upon said cover and said container to provide for movement of said cover in a generally horizontal plane relative to said container.

In testimony whereof, I have signed my name to this specification.

FRANK L. ORDWAY.
